UNITED STATES PATENT OFFICE.

OLIVER J. SHINER, DECEASED, LATE OF BAYONNE, NEW JERSEY, BY MAUD E. SHINER,
ADMINISTRATRIX, OF BAYONNE, NEW JERSEY.

METHOD OF AND APPARATUS FOR PURIFYING OIL.

1,099,622.

Specification of Letters Patent.

Patented June 9, 1914.

Application filed May 27, 1913. Serial No. 770,208.

To all whom it may concern:

Be it known that OLIVER J. SHINER, late a citizen of the United States, residing in Bayonne, in the county of Hudson and State of New Jersey, did invent certain new and useful Improvements in Methods of and Apparatus for Purifying Oil, of which the following is a specification.

This invention relates to methods of and apparatus for purifying oils wherein the distillate is treated with sulfuric acid to remove therefrom impurities which if present in the oil would create objectionable odor and color and would impair the burning qualities of the oil, the oil being subsequently washed and then treated with a suitable alkali to neutralize any acid that may remain after washing and also to combine with and remove any sulfur compounds which may be present. The method most commonly used is an intermittent one, a large tank or agitator being employed in which the different steps of the process are carried on, there being a period of rest or intermission between the steps and such agitators are not airtight, permitting the escape of vapors which can be saved.

As is well known by those skilled in the art, distillates, which are prepared in such manner as to have the fluidity and fire test suitable for the market, still possess an odor and a pale lemon color and also residual quantities of sulfur, which, of course, are objectionable. These are due in part to unavoidable destructive distillation and in part to the natural impurities in the crude oil. When washed with sulfuric acid (usually 66° Baumé) there is an oxidation, sulfonation and polymerization. Impurities in this condition are absorbed and chemically dissolved in the acid. After the equilibrium is established in the solutions, and the acid is settled and drawn off, the oil still contains in solution some of the sulfonic acids, imparting to it a brown reddish color and containing certain hydrocarbons of objectionable odor and color. In the application of water these residual compounds show preference for the water and should the washing be continued long enough such compounds would be entirely removed by the water. In practice, however, it is found more convenient to stop the washing earlier and neutralize the sulfonic acids with caustic soda. This gives rise to a small amount of sulfonates of soda in the

oil which are subsequently removed by the clay treatment. After the washing process the oil frequently contains sulfur compounds which, in the absence of elementary sulfur and sulfureted hydrogen, form with the plumbate of soda a yellow substance which is held in solution in the oil. After the oil has been saturated with plumbate of soda, sulfur is applied which acts as an oxidizing agent and precipitates sulfid of lead leaving the oil sweet with the original quantity of sulfur still contained therein.

It will be observed that the process hereinbefore described is an intermittent one and is for the most part performed in a single vessel or tank, called an agitator. There are numerous stops or intermissions in the process for agitation, settling, etc., and it requires several hours for any oil which has been supplied to the agitator to be withdrawn therefrom in a purified condition. The agitation in the process above described is effected by means of air injected into the container which is open or not air-tight, and there is a considerable loss of volatile gases which are liberated during the agitation. This loss is, in fact, quite serious.

According to the present invention the several operations from the point where the cooling or heating is commenced to the point where the clay is applied, is performed continuously, i. e., the impure oil is introduced at one end of the apparatus, allowed to flow continuously through the other parts thereof and is continuously withdrawn in a purified condition at the discharge end of the apparatus. The several operations in this invention are effected in air-tight containers connected by air-tight pipes and there is no loss of volatile gases during the process.

The invention relates especially to the refining, by means of sulfuric acid and alkali, of petroleum in the form of naphtha, burning oil distillate, or other suitable distillate, but it may be advantageously used for purifying undistilled products of petroleum in the crude or other forms. It will be understood, therefore, that the invention is applicable to petroleums or oils of various kinds.

In the accompanying drawings illustrating the invention, Figure 1 is a diagram of the apparatus for purifying oils constructed in accordance with this invention. Fig. 2 shows a section on the line 2-2 of Fig. 1.

and illustrates the washing tanks and some of their pipe connections. Fig. 2^a is a detail view of one of the sprinklers preferably used in the tempering and washing tanks. 5 Fig. 2^b is a detail view of a form of air inlet valve that may be used. Fig. 2^c is a detail view partly in side elevation and partly in section showing particularly how oil and water enter and leave the tempering tanks. 10 Fig. 3 shows a vertical central section through one of the mixers forming part of the apparatus. Figs. 4, 5, and 6 are detail views of parts of the mixer.

The apparatus employed preferably comprises twelve tanks.—three tanks in which the oil is cooled or heated to bring it to the required temperature, three tanks for washing purposes, four settling tanks, and two mixing tanks.

20 The cooling or heating tanks A, A', A² are arranged in series, as shown, oil being pumped into the bottom of tank A at X, (Figs. 1 and 2^c) filling this tank and flowing from the top of the tank through the 25 pipe a to the bottom of tank A' in which tank it rises, overflows through the pipe a' and enters the bottom of tank A² which tank it fills and overflows at the top through the pipe a² and enters the bottom of the 30 settling tank C. The pipes a, a', and a² are provided with valves a³, a⁴, a⁵, and each tank is provided with a water-spraying device D which is connected by a pipe d with a manifold D', which manifold is connected 35 by pipes d', d², d³ with the hot water supply pipe E, the supply pipe E' for bottom water and the supply pipe E² for well water. The "bottom water" referred to comes from the 40 bottom of the tanks A, A', A² and is stored in a suitable receptacle and afterward brought in by pipe, as indicated in Fig. 1, and may be used for modifying the temperature of the oil in said tanks. This bottom water is usually at a temperature of 45 about 62° F. Each of the pipes d, d', d² is provided with suitable valves e, e', e². By operating these valves the spraying device D may be supplied with hot water, bottom water or well water, or a mixture of these 50 waters, as may be required for the purpose of obtaining the desired temperature in the oil. Each of the tanks A, A', A² is in like manner connected with the pipes E, E', E² and each of said tanks A, A', A² is provided 55 with a drain pipe F (Figs. 1 and 2^c) in the bottom for carrying off water and delivering it to a sewer pipe G. Said pipe F is also connected with a pumping-out line H. The drain pipe F is connected with said pipes 60 G and H in the manner clearly indicated in the drawings, valves f being employed to control the flow of liquid to either the pipe G or the pipe H. Each of the tanks A, A', A² is in like manner connected with the 65 pipes G and H. The oil continuously flows

from the pipe X to and through the several tanks A, A', A² where it acquires the desired temperature and it then passes to the settling tank C where any water that may still cling to the oil descends or is held at the bottom while the oil rises and passes out at the top through a pipe I which leads to a mixing tank J, the details of construction of which are shown in Figs. 3, 4, 5 and 6, and will be hereinafter more fully described. 70 The pipe I is provided with valves i, i', as shown. The number and sizes of the cooling or heating tanks and the number and sizes of the settling tanks employed may vary at different seasons of the year or in the treatment of different oils, naphtha, etc. 75

It will be understood that water of the proper temperature is supplied continuously through the spraying devices D and it comes in contact with the continuously 80 flowing oil, the water being heavier descends and passes the constantly rising oil.

In the summer time the temperature of the oil entering the cooling tanks is usually about 85° F. By treating the oil in the 90 several cooling tanks with water at a temperature of say 60° F. the oil may have its temperature gradually reduced to about 60° F. The temperature of the oil varies at different times and under different conditions, and the temperature of the water should be correspondingly varied in order to bring the oil to a temperature of about 60° F. before it is subjected to the acid 95 treatment.

The cooling tanks A, A', A² and the settling tank C are all closed air-tight and are joined by air-tight connections. The water admitted to the cooling tanks and which descends to the bottom thereof flows continuously to the sewer, the flow being regulated by suitable valves. The water settling in the tank C is drawn therefrom and passed to the sewer as often as required, gages being employed to show the water level. It 105 will be understood that the pumping-out line H is for the purpose of emptying the tanks throughout the system of oil when repairs are necessary and for other like purposes, and normally this pumping-out line 110 H is not in use, but is only employed occasionally.

Fresh acid (preferably 66° Baumé) from a suitable pump or other device for supplying acid under pressure is conveyed by a pipe X to the top of the mixer J and is mixed with oil in the manner hereinafter described. The acid passes downwardly through the oil and is drawn off as often as required through a pipe L provided with a valve l and it is conveyed as sludge-acid to any suitable receptacle. The oil which rises to the top of the mixer passes by means of a pipe M provided with a valve m to the bottom of a settling tank N where it is sepa- 120 125 130

rated from any acid which may cling to it, said acid settling to the bottom and being drawn off when required through a valved pipe n and passed to the pipe L which conveys it to any suitable receptacle for sludge-acid. The oil which continually rises in the tank N passes out through the top thereof through a pipe P provided with a check valve p and it enters the lower portion of a washing tank Q which is supplied with either hot water, bottom water, well water, or a mixture thereof through the pipes q, q', q^2 , said supply being controlled by the valves e, e', e^2 . Each set of pipes q, q', q^2 connects with a pipe O provided with a spraying device o Fig. 2^a. The first wash tank Q should be lead lined because the oil has commingled with it some weak acid which would attack an iron tank, and furthermore the oil is cooled or maintained at a relatively low temperature in the tank Q for a similar purpose, *i. e.*, so that the metal tank shall not be attacked by the weak acid in the said tank. There are two other wash tanks Q', Q^2 , which are supplied with water from the pipes E, E', E^2 in a similar way and each of said tanks Q, Q', Q^2 is provided with a discharge pipe R connected by pipes R', R^2 with the pipe G which leads to the sewer or to the pipe H through which oil may be pumped when emptying the system. The water supplied to the tanks Q, Q', Q^2 in the normal operation of the apparatus passes continuously through the pipe connections described to the sewer. The flow of the water may be regulated by the valves shown.

Suitable air inlet valves are applied to the tanks where required. In Fig. 2 such valves are shown at B and the other tanks in the system may be provided with such valves. The connecting pipes may, if necessary be equipped with air inlet valves as indicated at B' in Figs. 2 and 2^b. Such valves are necessary when emptying the system through the pumping-out line H , but when oil is being pumped through the tanks, such valves are, of course, closed. The air inlet valve B' shown in Fig. 2^b is of well known construction. It comprises a chamber b communicating with the pipe S connecting the wash tanks Q, Q' and valves b' provided with springs b^2 to open them. The valves are normally held closed by the internal pressure, but when this pressure is released the valves are opened by the springs. Similar valves are attached to the pipes S', S^2 . The tanks where required may be provided with air chambers B^2 as indicated in Fig. 2. These, as shown in Fig. 2, are connected with the pipes S, S' and S^2 . The air in the tanks and pipes when the system is being filled with oil, for the most part, passes out at the delivery end of the system, but some air lingers and such air will be forced up into air chambers, such as indi-

cated at B^2 , and the air pressure may be relieved, if necessary, from time to time, by means of air-relief cocks b .

The oil after rising in the tank Q passes out from the top thereof and flows by means of the pipe S having a valve s to the bottom of the tank Q' in which it rises and passes out from the top through a pipe S' having a valve s' and enters the bottom of the tank Q^2 where it rises and flows out from the top through a pipe S^2 having a valve s^2 and then enters the bottom of the settling tank T . It will be understood that the oil is washed as it flows through the tanks Q, Q', Q^2 and the temperature of the oil may be gradually raised by employing well water, warm water, hot water, or a combination thereof, as required. Preferably the temperature of the water admitted to the first tank Q is 64° F., that admitted to the second tank Q' is 75° F., and that admitted to the third tank Q^2 is 85° F. In this way the oil is raised to a temperature best fitted for the alkali treatment. In the settling tank T the oil is separated from any water which may pass over from the wash tanks with it, such water collecting at the bottom and being drawn off to the sewer pipe G as often as required. The tank T is connected by means of the valved pipes t, t', t^2 with the pipes G and H , and when the system is being emptied the valves may be so operated as to connect the tank T with the pumping-out line H . In this connection it will be observed that the settling tank T is provided with valved pipes e, e', e^2 connecting with the sewer pipe G and the pumping-out line H .

The oil separated from the wash-water flows out from the top of the settling tank T through a pipe U having valves u, u' and enters the bottom of another mixing tank V similar to the tank J hereinbefore referred to. Fresh lye (preferably 9° Baumé) is supplied under pressure through the pipe W to the top of the tank V and flows down through said tank meeting the oil rising therein and being thoroughly mixed with said oil in the manner hereinafter described. The bottom of the tank V is connected by a pipe V' having a valve v' with a pipe V^2 through which the spent lye flows continuously during the normal operation of the apparatus, the flow being regulated by the valve v' . The oil passes out through the top of the tank V through a pipe V^3 having a valve v^2 and enters the bottom of the settling tank Y which tank is also connected to the pipe V^2 through which spent lye is delivered as often as required. The purified or finished oil passes from the top of the tank Y through a pipe Z having a valve z to any suitable receptacle. Where naphtha is being treated it is not necessary to further treat it with clay in the manner hereinbefore referred to, but the naphtha when it

110

115

120

125

130

issues from the pipe Z is ready for final distillation and is then ready for the market. If kerosene is being purified, a further treatment with clay is necessary. For this purpose two or more tanks equipped with suitable agitating mechanism may be employed, the oil passing from the pipe Z being conveyed alternately to said tanks and thus the flow of oil may be continuous and the clay-
10 ing operation carried on concurrently.

As before specified, all of the twelve tanks are closed air-tight and are supplied with suitable gages, vacuum valves, etc. The check valve p is for the purpose of preventing water from passing from the tank Q to the settling tank N in case of accident, as where the supply of water or the pressure of water may exceed the pressure of oil, this valve p permits the oil to flow freely, as indicated by the arrow in Fig. 1, but it will close if the liquid tends to flow in the opposite direction.

The pipe P, as indicated in Fig. 2, is provided with a valve p' and this pipe connects 25 with a pipe Z', as indicated in Fig. 2. This pipe Z' also connects with a pump Z² which latter is connected by a pipe Z² with the pipe L. The pipe Z² is provided with a valve z^2 as indicated in Fig. 1. The pipe L, it will 30 be observed, connects with the tanks J and N so that by closing the valve p' the flow of oil to the wash tank Q may be stopped and the acid-water in the tank Q may be transferred to the pipe L, or oil from the mixer 35 J and tank N may be transferred to and put through the tank Q by means of the pump Z². In this way the acid may be washed out of the oil and this oil may be pumped out and transferred to a suitable receptacle 40 when emptying the system. When it is desired to stop the operation and entirely empty the pipes, the water and chemicals are first withdrawn from the tanks in the manner before described and then the pumping-out line H is connected by means of the 45 valves, before referred to, with the tanks and said tanks may be emptied of the oil which they contain, the vacuum valves, before referred to, assisting in the emptying 50 of the tanks in a well known way.

The fact that this process may be carried on continuously is largely due to the use of mixers for bringing the acid and oil and the alkali and oil into intimate contact with 55 each other and in a sub-divided or atomized condition. It is largely for this reason that the periods of settling heretofore necessary are avoided.

The mixing apparatus, which is prefer- 60 ably employed, and which in practice has been found to be most efficient is illustrated particularly in Fig. 3 of the drawings to which reference is now invited.

This mixing apparatus comprises a cyl- 65 inder 1 standing vertically, closed at oppo-

site ends by heads 2, 3, and resting on any suitable foundation 4. Centrally arranged within the cylinder is a vertical shaft 5 resting in bearings 6 at its lower end and passing through a stuffing box 7 carried by the upper head 2. The shaft 5 also passes through a shaft mounting 8 which may be provided with ball-bearings 9 and at its upper end the shaft carries a beveled pinion 10 meshing with a corresponding pinion 11 70 on a driving shaft 12. The cylinder 1 is provided with man-holes 13 and 14 and it is equipped on its side near its lower end with an inlet 15 for oil and at the top with an outlet 16 for oil. It is also provided with an inlet 17 at the top for acid or lye. Otherwise the container may be of any suitable construction. Within the cylinder 1 is arranged a vertical series of pans 18. These have a general conical shape being of the 75 general construction shown in Figs. 4 and 5. Each of the pans 18 is secured at its periphery 19 to the side wall of the cylinder 1 in any suitable way and it is divided preferably into four pockets by means of radial 80 partitions 20. The pan is open at the top and has a sloping bottom 21 provided with a central opening 22 surrounding the shaft 5. The pans 18 are spaced apart, as shown, and between each two pans are arranged 85 perforated plates 23, 24. Each pair of plates is attached to a hub 25 secured to and revolving with the shaft 5. One means of securing the hub 25 to the shaft is indicated at 26. These plates, which are circular 90 and correspond in form with the interior diameter of the cylinder 1, extend close to the walls of the cylinder without touching it, being free to revolve within the cylinder. The upper plate 23 of each pair of plates is 95 perforated preferably with $\frac{1}{4}$ inch holes preferably spaced one inch between centers and the bottom plate 24 of each pair is preferably perforated with $\frac{1}{8}$ inch holes preferably spaced $\frac{1}{2}$ inch between centers. 100 All of the plates are similarly constructed and are arranged as clearly shown in Fig. 3 of the drawings. In order to provide a bearing for the shaft 5, about midway between the upper and lower ends of the cylinder 1, one of the pans is provided with a hub 27 which is attached to the partitions 20 in the manner shown in Fig. 4. This provides means for steadyng the shaft 5 and is desirable inasmuch as the mixer may 105 be of considerable height. The oil, which enters at 15, passes up through the openings 22 of the several pans 18 while the acid or lye, which enters at 17, descends through the oil to the bottom of the mixer and flows 110 out at 28. The oil passes up through the openings 22 in the pans 18 and then up through the perforated plates. The acid or lye first enters the uppermost pan 18, passes 115 down through the opening 22 of this pan 120

and is received by the uppermost pair of plates 23, 24. Each pan serves to carry the chemicals into the center of the mixer and drop them down onto the revolving plates which throw them out by centrifugal force 5 toward the shell of the mixer, and the oil, naphtha or other liquid being treated passes up through the center of the pan while the chemicals are passing down through said openings and are at this time being mixed.

10 This apparatus insures an intimate mixture of the chemicals with the oil, the particles being thoroughly atomized and for this reason the flow of oil through the mixer 15 may be made continuous. It is largely due to the use of mixtures of the kind described that the process may be performed continuously.

The mixer J for treating the petroleum 20 with sulfuric acid of sufficient strength to attack the hydrocarbons of objectionable odor and color is so constructed that while it thoroughly mixes the oil and acid, it permits the acid to pass downward and the 25 oil to pass upward and the conditions are such as to cause the formation of a viscous liquid of blackish or brownish coloration with oily constituents of objectionable odor and color, known as "acid sludge"; furthermore 30 the entrained moisture in the oil is absorbed by the partially spent acid in the lower portion of the mixer, while the oil is treated in the upper portion with the stronger acid, the operation being progressive, the thus dried oil being subjected to 35 acid of progressively increasing strength. In the mixer for the alkaline treatment the conditions are the same and the entrained moisture entering with the oil at the lower 40 part of this mixer is absorbed at the lower portion of the tank and the thus dried oil is treated in the upper portion of the tank by the alkali.

When a moist petroleum distillate is subjected 45 to the effect of spent or partly spent sulfuric acid (*i. e.* acid sludge), it has a tendency to form therewith though not immediately objectionable hydrocarbons, which hydrocarbons may be absorbed by the petroleum 50 distillate, giving it sometimes a disagreeable odor. It is advisable, therefore, to shorten the time in which particles of the sludge and particles of the treated petroleum distillate are together, as much as possible; and any 55 process which contemplates the curtailment of the time during which certain particles of the sludge and certain particles of the treated distillate are in contact, helps to produce a superior product. In the process 60 of this application, the time of mutual contact is shortened by several agencies, and the extent of such contact is increased. In the first place, the current of the distillate and of the purifying agent are made to flow 65 in opposite directions, and these directions,

in the present mixing chambers, are up and down. Merely dropping the heavier purifying solution, acid sludge, or sulfuric acid gradually forming sludge, through the ascending current of the distillate, is not 70 enough to insure the proper extent of contact between the two. This contact may be extended by stirring or agitation, but the peculiar effect of my rotating agitator plates 23, 24, greatly enhances the extent of contact 75 between the drops or portions of the heavier acid and the hydrocarbon by forcing or flinging these drops or guttules sidewise across the ascending current, so that there is a tendency for the acid or sludge to accumulate somewhat, at the peripheries of 80 these stirrers where it is again flung or swirled centerwise into the mass of oil or naphtha while its gyratory impetus is deadened at the moment it comes into contact 85 with the plates 20. It then drifts through the next opening 22, to be again caught and flung guttulously through the ascending mass of oil or naphtha. The alternation 90 of these phases of centrifugal action with phases of downward drift due to gravity effect, insures a constant incipient separation and remixing of the two, whereby the contact of the little drops or guttules of the acid with the mass of the distillate, is magnified 95 or extended to a very great extent. The outward flinging of the particles of acid, due to centrifugal action, necessarily involves a corresponding inward flow of an equal quantity of distillate which also adds 100 to the effect. Probably also, as the particles or drops of acid or sludge draw toward the bottom of the mixing cylinder, and as they become thicker or more viscid, owing to the churning action of the agitators, they have 105 some tendency to agglomerate or to "gather" into larger masses, thus insuring their collection more quickly in the bottom of the cylinder, than would happen if such drops were merely allowed to drift or fall 110 down, even if their fall were broken by beaters or paddles of the usual mixing or agitating type. In the present instance, the traverse of contact of say a single drop or 115 guttule of the acid in contact with the distillate, is greatly extended through a given time, thus obviating the objectionable result likely to arise when to sludge and distillate are too long a time in contact, besides shortening the length of time the apparatus is in use, 120 thus diminishing overhead cost and cutting down the quantity of acid necessary, as elsewhere stated.

When a mixer is employed for the treatment with alkali pure or partly spent, the 125 alkali salts or compounds formed have a tendency to emulsify with the distillate, some times, and their separation therefrom is effected with difficulty. By shortening the time of treatment, and reducing the 130

quantity of alkali, this tendency is likewise greatly reduced or entirely eliminated.

The dimensions of the mixers may be varied. In practice the mixer tank has been 5 25 feet high and 7 feet in diameter, being provided with ten groups or pairs of revolving plates and a corresponding number of pans. The plates are preferably placed about 2 feet apart and the two plates of 10 each group are preferably 3 inches apart. Burning oil distillate at a temperature of about 60° F. may be supplied at the bottom of the tank J at the rate of 300 barrels (40 gallons to the barrel) per hour and 15 sulfuric acid of 66° Baumé may be supplied at the top of said tank in sufficient quantity to produce the desired effect on the petroleum. It has been found that about twenty per cent. less acid may be supplied 20 than would be required to produce an equal purification in accordance with prior current practice. About five and five-eighths pounds of sulfuric acid of 66° Baumé per barrel (40 gallons) of a burning oil distillate is required according to this invention, while an equal amount of distillate according to the old method requires seven pounds of such acid. The perforated plates 25 may be revolved at the rate of thirty-eight revolutions per minute, but the speed may be somewhat varied.

Naphtha may be introduced more rapidly than burning oil distillate, say at the rate of 450 barrels per hour, and a smaller amount 30 of sulfuric acid per barrel may be employed, say three pounds of sulfuric acid of 66° Baumé per barrel, whereas by the old method five pounds of acid were necessarily used. It will thus be seen that not only 35 is the operation continuous, but there is a large saving of acid in the use of the present invention. While the best results are obtained by passing the oil and chemicals in opposite directions, it is conceived that 40 somewhat similar results may be obtained in other ways and all of the claims herein-after made are not necessarily limited to the passage of these liquids in opposite directions, but it is important that the chemicals and petroleum should be intimately 45 mixed in the manner before specified to produce the results pointed out. The entrained moisture in the oil is, as before specified, withdrawn therefrom in the same vessel 50 where it is treated with the specified chemical and this is preferred to an apparatus where said moisture is absorbed in another vessel.

It will be observed that the tanks are all 55 closed airtight so that danger from fire is reduced to a minimum. The easily volatile gases are saved, whereas in the old method many of these gases were lost because the agitators employed were not closed airtight. Furthermore by this continuous

method there is a large saving of acid because when the oil and acid are passing through the mixer there is a thorough mixing of the two liquids, whereas in the old system the acid does not come in contact 70 with every particle of the oil and it is necessary to use a relatively large amount of acid to obtain the desired results.

What is herein claimed as the invention of the said OLIVER J. SHINER, is—

1. The herein-described continuous process of purifying oil, which consists in mixing with the oil at a relatively low temperature, and while being rotated and flowing continuously, sulfuric acid while being rotated and flowing in an opposite direction to that of the oil, separating from the oil while still flowing the acid sludge produced, washing the oil with cool water while flowing to cleanse it from said acid, further 80 washing the oil with water at a higher temperature to raise the temperature of the oil for the subsequent alkali treatment, separating the wash-water from the flowing oil, mixing with the oil while it is flowing an alkaline solution while the latter is flowing 90 in an opposite direction to that of the oil and separating from the oil while still flowing the alkaline solution.

2. The herein-described continuous process of purifying oil, which consists in cooling the oil with water to reduce it to a temperature of approximately 60° for the acid treatment, separating the water from the oil, mixing with the oil while being rotated 100 and while flowing continuously sulfuric acid flowing in an opposite direction to that of the oil, separating from the oil while still flowing the acid sludge produced, washing the oil to cool it and to remove acid therefrom, treating the oil with water to raise its temperature for the alkali treatment, separating the wash-water from the flowing oil, mixing with the oil while it is flowing and while at a higher temperature than 110 during the acid treatment an alkaline solution while the latter is flowing in an opposite direction to that of the oil and separating from the oil while still flowing the alkaline solution.

3. The apparatus herein-described for purifying oil while the same is flowing continuously without the loss of volatile gases, comprising an airtight mixer, a pipe conveying oil to the bottom thereof, a pipe conveying acid to the top thereof, means in the mixer for rotating the oil, and subdividing and thoroughly agitating it with the acid, means for separating from the oil the acid sludge produced, a washer to the bottom of which the oil is admitted, means for supplying water to the top of the washer, means for withdrawing the wash-water from the oil, means for raising the temperature 120 of the oil, an airtight mixer to the lower 125 130

end of which the washed oil is admitted, means for admitting an alkaline solution at the top of said mixer and means for separating the spent alkaline solution from the oil.

4. The apparatus hereindescribed for purifying oil while the same is flowing continuously without the loss of volatile gases, comprising a series of airtight tanks through 10 which the oil passes, means for admitting water to said tanks to cool the oil therein, an airtight settling tank through which the cooled oil passes and in which it is separated from water carried with it, an airtight mixer to the bottom of which the cooled oil is conveyed, a pipe conveying acid to the top of said mixer, means in the mixer for subdividing and thoroughly agitating the oil and acid therein, means for separating 20 from the oil the acid sludge produced, an airtight wash tank to the bottom of which the oil is admitted, means for supplying water to the top of said wash tank, means for withdrawing the wash-water from the oil, means for raising the temperature of the oil, an airtight mixer to the lower end of which the washed oil is admitted, means for admitting an alkaline solution at the top of said mixer, and means for separating 30 the spent alkaline solution from the oil, the organization being such that the oil passes continuously through the apparatus and receives an acid and alkali treatment in a closed system without the loss of volatile 35 gases.

5. The hereindescribed apparatus for treating petroleum distillate comprising, means for supplying the distillate under pressure, means for regulating the temperature of the inflowing distillate; a closed mixing vessel to the bottom of which the temperature-regulated distillate is continuously conveyed and in which it rises, to the top of which acid is continuously delivered 40 and from the bottom of which the acid sludge produced is withdrawn, mechanically-actuated means within the mixing vessel for agitating the reversely flowing distillate and acid and effecting an intimate mixture thereof; means connected 45 with said mixing vessel for washing and regulating the temperature of the distillate continuously discharged from the top of said vessel; means for continuously conveying 50 the washed and temperature-regulated distillate from the washing and temperature-regulating means; a closed mixing vessel to the lower end of which the washed distillate is continuously delivered; means 55 for continuously delivering an alkaline solution into the top of said last mentioned mixing vessel; mechanically-actuated means within said vessel for agitating the reversely flowing distillate and alkaline solution 60 to effect an intimate mixture thereof;

means for discharging the spent alkaline solution from the bottom of said mixing vessel; and means for continuously discharging the distillate from the top of said mixing vessel.

6. The process of purifying a petroleum distillate which consists in subjecting a continuously rising current of such distillate to the influence of a continuously descending heavier current of a chemical purifying agent and insuring intimate contact of the said distillate and agent by alternate subjection to the effect of centrifugal action and of gravity, which causes particles of the descending purifying agent to be 70 thrown sidewise with particles of the distillate while the latter is ascending.

7. The process of purifying a petroleum distillate which consists in discharging downward through a rising current, of such 75 distillate, a chemical purifying agent heavier than the distillate and interrupting the flow at intervals by causing the purifying agent to pass sidewise across the rising current of the distillate in a series of finely 80 divided particles or guttules while the distillate is ascending.

8. The process of purifying a light petroleum distillate which consists in passing downward through a rising current of such 90 distillate, an aqueous solution of a suitable chemical purifying agent, and interrupting the downward passage of the one and the upward passage of the other by flinging transversely through the rising current of the 100 distillate, continuously, the chemical purifying agent in a state of minute subdivision, causing the purifying agent to descend a step by gravity, again flinging it across and through the rising distillate and repeating 105 the gravity and flinging steps for the purpose specified.

9. A process of purifying a petroleum distillate which consists in discharging against a large slow moving, upwardly rising current of said distillate a small downwardly directed current of a heavier liquid chemical purifying agent, imparting to said purifying agent, at intervals a centrifugal 110 sidewise movement in a guttulous condition, and alternating with said centrifugal movement, movements downward by gravity, near the center of the upwardly rising slow moving current of the distillate.

10. An apparatus for purifying petroleum distillates which consists of an enclosed circuit consisting of upright chambers, and pipes extending from the top of each chamber to the bottom of the next, means for passing a petroleum distillate through the circuit in a direction to cause it to enter each chamber near the bottom, means in certain of said chambers for discharging chemical purifying agents against said current, centrifugally acting means in 115 120 125 130

said chambers for effecting a succession of discharges of said purifying agent in a guttulous condition across and against the current of the distillate, and a succession of 5 means alternating with the centrifugal means for deadening gyratory centrifugal impetus and permitting the purifying agent to sink or drift downward against the rising current of the distillate.

In testimony whereof I affix my signature to in the presence of two witnesses.

MAUD E. SHINER,
Administratrix of the estate of Oliver J. Shiner, deceased.

Witnesses:

LLOYD B. WIGHT,
A. N. MITCHELL.
